UNITED STATES PATENT OFFICE.

IRWIN W. PIERCE, OF NEW YORK, N. Y.

RAILWAY-SIGNAL.

1,023,440.

Specification of Letters Patent.

Patented Apr. 16, 1912.

Application filed June 9, 1910. Serial No. 566,023.

To all whom it may concern:

Be it known that I, IRWIN W. PIERCE, a citizen of the United States, residing in the city of New York, borough of Brooklyn, 5 in the county of Kings and State of New York, have invented a certain new and useful Improvement in Railway-Signals, of which the following is a specification.

The invention relates to signals operated 10 by the passage of the train, and is especially designed to actuate one of a series of electrically operated signals selected by an operator on the train, to indicate destination, route to be followed, or analogous purpose.

15 The primary object of the invention is to provide means actuated from the moving train, which shall reliably operate a signal at a more or less distant point.

Another important object is to maintain 20 such signal to the exclusion of others until the train has passed a predetermined point and operated a release or make-and-break contact which returns the electric circuits and connections to the original condition 25 ready to be operated by a succeeding train.

A further object is to provide an arrangement of the mechanical portions of the apparatus by which the latter may be easily installed and but little exposed to unintentional or accidental contact with suspended 30 or other projecting portions of the moving train, and which will permit the train to be moved in the reverse direction without affecting the signal or deranging the apparatus, and, generally to provide a signaling 35 system of this class which shall be positive in operation, simple in its mechanical and electrical construction and not liable to derangement.

40 The invention consists in certain novel features of construction and arrangement of parts by which the above objects are attained, to be hereinafter described.

The accompanying drawings form a part 45 of this specification and show an approved form of the invention.

Figure 1 is a side elevation of the track mechanism and train mechanism, a portion of the latter being shown in vertical section.

50 The outlines of the car and track are indicated by dotted lines. Fig. 2 is a corresponding end elevation of the train mechanism. Fig. 3 is a plan view of the same parts, seen from below. Fig. 4 is a vertical

section taken transversely of track and 55 showing an end elevation of the track mechanism. The succeeding figures are on a larger scale. Fig. 5 is a plan view of the track mechanism, with a portion of the protecting casing in horizontal section. Fig. 60 6 is a corresponding side elevation with the casing in vertical section. Fig. 7 is longitudinal section taken on the line 7—7 in Figs. 8 and 9. Fig. 8 is an end elevation 65 of the same parts as seen from the right in Figs. 5, 6 and 7. Fig. 9 is a similar view of the opposite end. Fig. 10 is a face view of a switch carried by the car. Fig. 11 is a diagram showing the electric circuits and 70 connections.

Similar letters of reference indicate the same parts in all the figures.

A A are the rails, B a car, shown in dotted lines, having wheels B¹ mounted on suitable trucks, not shown, supporting the car in the 75 usual manner. Attached to a portion of such truck and projecting downwardly therefrom is a centrally located plate B² having on each side of the lower face a rib or shoe B³ between which are arranged a 80 series of strips or contact-bars b, b¹, b², b³, b⁴ extending longitudinally of the plate and insulated from the latter and each other.

Located at each end of the car conveniently to the motorman's position, is a 85 switch C having four contact points c¹, c², c³, c⁴ connected by wires in a cable C¹ to the contact-bars b¹, b², b³, b⁴ on the plate B² and connecting the bar b to the switch-lever.

The shoes B³ are so positioned relatively 90 to a trip-lever between the rails as to present one or the other to such lever and tilt the latter by contact therewith regardless of which end of the car is serving as the front, and by thus tilting the lever present 95 a series of contact-fingers to the contact-bars b, b¹, b², b³, b⁴, as will be described.

D is a bed-plate securely bolted to the ties or otherwise fastened to the roadbed between the rails and having attached thereto a shallow casing D¹ open at the top and having oppositely inclined closed ends D². In the casing at one side of the center line of the rails is mounted a transverse shaft A¹ carrying a trip-lever A² having a head A³ with 100 beveled or inclined faces adapted to be struck by either of the shoes B³ and tilted by such contact. The lower portion of the 105

lever is bifurcated and incloses above the shaft A¹ a tubular sleeve A⁴ attached to the legs of the lever by trunnions A⁵.

A rod A⁶ extends longitudinally through the sleeve A⁴ and carries two oppositely placed adjustable collars A⁷ serving as abutments for two helical springs A⁸ A⁹ encircling the rod and abutting at their inner ends against the ends of the sleeve and exerting their expansive forces in opposition to each other to maintain the lever normally in the vertical position but permit its tilting movement in either direction. The rod A⁶ terminates at one end in a yoke A¹⁰ pivotally connected to a crank-arm E¹ on a shaft E extending transversely of the casing and supported in bearing D³ D³ on the bed-plate D.

On the shaft E is fixed a wide horizontally disposed arm E² carrying a series of flexible metallic fingers e, e¹, e², e³, e⁴ arranged side by side, extending longitudinally of the casing and track, and lying when depressed or in the normal position, flush with or slightly below the plane of upper faces of the rails A A. The fingers are spaced to correspond to the contact-bars b, b¹, b², b³, b⁴ carried on the car and are arranged to contact therewith when elevated.

30 The passage of the shoes B³ in the direction indicated by the arrow in Fig. 1, tilts the trip-lever and through the spring A⁸ induces a yielding endwise movement of the rod A⁶ and partial rotation of the shaft E which raises all the fingers simultaneously into the position shown by the dotted lines in Fig. 7 in which position they are wiped by the contact-bars on the moving car.

Each finger is insulated from the others 40 by sheets of insulating material E⁵ on the upper and lower faces of the arm E², and the latter with the fingers is returned to the depressed position by the retractile action of a series of vertically arranged helical 45 springs E⁴ E⁴ one for each finger and in electric connection therewith. The lower ends of the springs are insulated from each other and the plate D and each is provided with a binding post E⁵ through which electric connection is maintained with its finger.

A lug E⁶ on the arm E² serves to limit the upward movement of the fingers by contact with an upturned flange F¹ on an adjustable stop F mounted on the plate D.

55 On the crank-arm E¹ at the point E⁷ is pivoted one end of a connecting-rod or link G made in two portions bolted together to permit adjustment as to length, and the other end is pivotally joined to the short 60 arm G¹ of a bell-crank lever G², the long arm of which carries a contact point adapted to make electric contact with an insulated segmental plate G³ on a bracket G⁴ adjustably mounted on the bed-plate D, when 65 the trip-lever A² is tilted to lift the fingers

e, e¹, e², e³, e⁴ and slightly in advance of their rise to the plane of contact with the bars b, b¹, b², b³, b⁴.

The springs A⁸ and A⁹ contribute the desired yielding quality to the action of the trip-lever. The spring A⁸ allows the rise of the fingers to be checked at an elevation determined by the position of the flange F¹ relatively to the lug E⁶ and permits the trip-lever to continue its movement by idly compressing such spring, while the other spring A⁹ allows the trip-lever to be tilted in the opposite direction, as in the backing movement of a car, without other effect than the idle compression of that spring. By properly adjusting the tension of the springs, through the nuts A¹¹ A¹², the trip-lever when released is returned to the normal approximately upright position.

N is a lever, only partially shown, mounted between the rails A A in the path of the shoe B³ and serves when struck by the latter to operate a switch N¹, see Fig. 11, and momentarily close a circuit through which the signal and its circuits are returned to normal, as will be described. The lever N is located at any desired point in advance of the train at which the signal is to be obliterated.

In describing the operation of the apparatus and the electric circuits and connections as shown in Fig. 11, it will be assumed that the signals m¹, m², m³, m⁴ are electric lamps indicating to a switchman the destinations of approaching trains and enabling him to set his rail switches to correspond to the destination or route indicated by the glow of each lamp as selected by the motorman through his electric switch C on the car or train, but it will be understood that other signals than lamps may be operated and for other purposes than of "router" or annunciator.

The lamps may be located on the station platform, in a switch tower, or other situation, depending on the purpose for which the signals are to serve.

Assuming the lamp m¹ to be selected as the signal to be set, the motorman on approaching the trip-lever A² moves his switch C at either end of the car serving as the front, to the contact-point e¹. When the shoe B³ on the plate B² strikes the trip-lever A² the first effect is to move the bell-crank lever G² and make contact at G³ and condition the circuits for service, the further movement of the trip-lever raises the fingers e, e¹, e², e³, e⁴ into contact with the bars b, b¹, b², b³, b⁴ on the moving car and a circuit is established as follows:—Starting from the battery M, or other source of current, through the normally closed switch H¹ and wire H² to contact point G³, finger e, contact-bar b, wire H³ and switch lever C, switch point e¹, contact-bar b¹, finger e¹, wire g¹ to electro-

magnet switch J, energizing its magnet and closing the switches J¹ J², thence through the wire g² and normally closed magnet switch K and wire g³ to the battery M. The current through this "track circuit" energizes the magnet J and closes both switches J¹ J² simultaneously, current thus passes from M through j and j¹, switch J¹ and wire j² to the lamp or signal m¹ and thence by return wire j³ to the battery M thus completing the "signal circuit" and setting the signal. The switch J² which closes at the same time, completes a circuit from g¹ through k, switch J² and wire k¹ to electro-magnet H and wire k² to the battery M and opens the track circuit so that danger of short circuiting through the fingers e, e¹, e², e³, e⁴ is avoided and no other signal is permitted to be set from the train through inadvertence or neglect in throwing off switches C on other cars of the train. The circuit which energizes the magnet J to act in this manner is as follows:—When the signal circuit described above is completed, the magnet J closes switch J² and energizes magnet H through a circuit traced from the battery M through wire k² to magnet H, wire k¹ to switch J², wire k and magnet J, wire g², switch K, wire g³ to the battery, the effect of closing this circuit is to break the track circuit and prevent short circuiting or inadvertent attempts to set another signal, as pointed out above. The circuit through the signal remains closed, holding the switches J¹ J² in closed condition with signal set, until the shoe B³ on the car strikes the release lever N located at a point in the track beyond the trip-lever A² and momentarily closes the switch N¹ which closure completes a release circuit through the wire n¹ from j³, and wire n² leading to the magnet K¹, thence through wire n³ to g³ and the battery M, energizes magnet K¹, breaks the circuit through switch K and permits switches J¹ J² to return to original open positions, obliterates signal m¹ and conditions the track circuit and signal circuits for setting the same signal m¹ or either of the others m², m³, m⁴ as selected by the operator on the succeeding train.

The track mechanism is strong and compact, requiring but little depth for its installation and operation, the only part lying above the rail surface being a portion of the thin head A³ of the trip-lever; and the beveled faces of such head with the inclined ends D² D² of the casing in which the mechanism is inclosed reduces to a minimum the danger of derangement or of accidentally setting a signal by contact or engagement with hose connections, chains, or other downwardly projecting portions of the car equipment.

Although the trip-lever and its associated

mechanism is shown as located between the rails, and the contact plate described as located beneath the car, it will be understood that these parts may be placed to co-act at any other location or level.

70

Other modifications may be made in the mechanism and in the arrangement of electric circuits as may be found necessary or desirable in conditioning the system for service in performing the various functions to which it may be adapted.

75

I claim:—

1. A shoe and a plurality of contact bars carried by a car, a lever mounted in the path of said shoe to be directly engaged and moved by said shoe, a plurality of fingers mounted on a different support from that of said lever for coöperation with the bars, means for actuating said fingers through the movement of the lever, and a signal actuated by the contact of said bars and fingers.

80

2. A shoe and contact-bars carried by a car, a lever mounted in the path of said shoe and arranged to be moved by the passage of said shoe, fingers connected to said lever and arranged to be moved into the paths of said contact bars by the movement of said lever, an electric switch operatively connected with said lever and operated by the movement of the latter in advance of the contact of the said fingers and contact bars, a circuit controlled by said switch and said fingers, and a signal actuated by the closing of said circuit.

90

3. In an apparatus of the character set forth, a shoe carried by a car, a lever arranged to be moved by contact with said shoe, a shaft, a crank arm thereon, a rod connected to said lever and crank arm, contact means on the shoe, yielding means acting on said rod in the direction of its length, and a plurality of contact fingers movable with said shaft for coöperation with the contact means on said shoe.

105

4. In an apparatus of the character set forth, a shoe carried by a car, contact means carried by the car, a lever arranged to be moved by contact therewith of said shoe, a shaft, a crank arm thereon, a rod connected to said lever and crank arm, yielding means acting on said rod in the direction of its length, a plurality of contact fingers movable with said shaft for coöperation with said contact means, and an adjustable stop for limiting the movement of said shaft and fingers.

110

5. In an apparatus of the character set forth, a shoe carried by a car, a lever arranged to be moved by contact with said shoe, a shaft and a crank-arm thereon, a rod connected to said crank-arm and extending through said lever, abutments on said rod, springs on opposite sides of said lever on said rod, each abutting at one end against said lever and at the other against said

125

120

130

abutments, and contact-fingers mounted on said shaft.

6. In an apparatus of the character set forth, a bed-plate adapted to lie between the rails of a railway, a lever mounted in said plate and arranged to be moved by contact with a shoe carried by a car on such rails, a shaft mounted on said plate, a crank-arm on said shaft, a rod connecting said crank-arm and lever, one or more contact-fingers mounted on said shaft to move therewith, and a casing having an opening for said lever and fingers and having closed inclined ends.
- 15 7. In an apparatus of the character set forth, a bed-plate adapted to lie between the rails of a railway, a lever mounted in said plate and arranged to be moved by contact with a shoe carried by a car on such 20 rails, a shaft mounted in bearings on said plate, and means connecting said lever and shaft for partially rotating the latter, an arm on said shaft, a plurality of contact fingers carried by said arm, an adjustable 25 stop beneath said shaft, and a lug on said arm adapted to strike said stop and limit the movement of said shaft.
8. In an apparatus of the character set forth, a bed-plate adapted to lie between the rails of a railway, a lever mounted in said plate and arranged to be moved by contact with a shoe carried by a car on such rails, a shaft mounted in bearings on said plate, a crank-arm on said shaft and yielding 30 connections from said lever to said crank-arm, a series of insulated fingers carried by said shaft and raised by the movement of said lever in one direction, and a spring for each finger serving to depress the 35 series when the latter is released and also as an electric connection for each of such fingers.
- 40 9. In an apparatus of the character set forth, a shaft and a series of contact fingers carried thereby, a crank-arm on said shaft, a bifurcated lever arranged to be tilted by contact with a moving shoe, a tubular sleeve mounted in the bifurcation of said lever, a rod connected to said crank-arm and extended loosely through said sleeve, an abutment on said rod on each side of said lever, and springs incircling said rod and abutting at one end against the opposite ends of said 45 sleeve and at the other against said abutments.
- 50 10. In apparatus of the character set forth, a plate carried beneath a car, a switch on the car, a series of contact-bars and a shoe on said plate, electric connections from each of said bars to the switch on said car, a lever mounted between the rails and ar-

ranged to be tilted by contact with said shoe, a series of contact fingers elevated by such contact of said shoe and lever into the paths of said contact-bars to complete an 55 electric circuit through a selected bar determined by the position of said switch.

11. In an apparatus of the character set forth, a shoe and contact-bars carried by a car, an electric switch on the car connected to said bars, a lever mounted in the path of said shoe and arranged to be tilted thereby, a series of fingers moved into contact with said bars by the tilting of said lever, a circuit through said bars closed by said lever, said 75 circuit including fingers and a switch, a signal, an electric circuit including said signal and closed by the closing of said first-named circuit, and means actuated at the closing of said signal circuit for opening 80 said first-named circuit.

12. In an apparatus of the character set forth, a shoe and contact bars carried by a car, an electric switch on such car connected to said bars, a lever mounted in the path 85 of said shoe and arranged to be tilted thereby, a series of fingers mounted to be moved into contact with said bars by the tilting of such lever, a signal, an electric circuit including said signal, a circuit including means by which said first-named circuit is closed, means actuated at the closing of said signal circuit for opening the last-named circuit, and a contact actuated by the passage of the car for opening said 95 signal circuit.

13. In an apparatus of the character set forth, a shoe and contact-bars carried by a car, an electric switch on such car connected to said bars, a lever mounted in the path of said shoe and arranged to be tilted thereby, a series of circuits, a series of fingers moved into contact with said bars by the tilting of said lever each adapted to close one of such series of circuits through said bars, fingers 100 and switch, as selected by the position of the latter, a series of signals, a series of circuits each including one of said signals and closed as selected by the closing of the selected circuit, means actuated by the closing 110 of the selected signal circuit for opening such selected circuit, and a release circuit momentarily closed by a further movement of the car, for opening such signal circuit.

In testimony that I claim the invention 115 above set forth I affix my signature, in presence of two witnesses.

IRWIN W. PIERCE.
